[57] **CLAIM**

The ornamental design for a diamond circular saw blades, as shown and described.

DESCRIPTION

FIG. 1 is a plan view of a diamond circular saw blade in accordance with the present design;

FIG. 2 is a front view thereof;

FIG. 3 is a bottom view thereof;

FIG. 4 is a left side view thereof;

FIG. 5 is a right side view thereof;

FIG. 6 is a sectional view taken along line 6—6 of FIG. 2;

FIG. 7 is a sectional view taken along line 7—7 of FIG. 2; and

FIG. 8 is an enlarged sectional view enclosed by lines 8—8 of FIG. 6.

A rear view is omitted because it is symmetrical to the front view.

FIG. 9 is a plan view of another diamond circular saw blade in accordance with the present design;

FIG. 10 is a front view thereof;

FIG. 11 is a bottom view thereof;

FIG. 12 is a left side view thereof;

FIG. 13 is a right side view thereof;

FIG. 14 is a sectional view taken along line 14—14 of FIG. 10;

FIG. 15 is a sectional view taken along line 15—15 of FIG. 10; and

FIG. 16 is an enlarged sectional view enclosed by lines 16—16 and of FIG. 14;

FIG. 17 is a plan view of a further diamond circular saw blade in accordance with the present design;

FIG. 18 is a front view thereof;

FIG. 19 is a bottom view thereof;

FIG. 20 is a left side view thereof;

FIG. 21 is a right side view thereof;

FIG. 22 is a sectional view taken along line 22—22 of FIG. 18;

FIG. 23 is a sectional taken along line 23—23 of FIG. 18; and,

FIG. 24 is an enlarged sectional view enclosed by lines 24—24 and of FIG. 22.

The rear views are omitted because it is symmetrical to the front view.
